ELECTRICAL APPARATUS

Charles W. Wyman, Claremont, N. H., assignor
to Sullivan Machinery Company, a corporation
of Massachusetts

Application May 20, 1931. Serial No. 538,810

16 Claims. (Cl. 172—179)

My invention relates to electrical apparatus, and more particularly to electrical controlling apparatus for reversible motors.

An object of my invention is to provide controlling apparatus. Another object of my invention is to provide improved starting, stopping and reversing mechanism for an electric motor. A further object of my invention is to provide an improved starting, stopping and reversing mechanism for an electric motor in which starting is impossible except in predetermined positions of the reverse switch and in which movement of the reverse switch is precluded both when current is being supplied to the motor and, after the interruption of current supply to the motor from an external source, while the motor is rotating at such speed that there is material regenerative current flowing in its armature. Other objects and advantages of my invention will hereinafter more fully appear.

In the accompanying drawings there is shown for purposes of illustration one form which this invention may assume in practice.

In these drawings,

Fig. 1 is a horizontal sectional view through a chamber in a mining machine frame in which the illustrative embodiment of my improved controlling mechanism is in part arranged.

Fig. 2 is a top view of the same chamber with a cover plate removed, showing the parts therein.

Fig. 3 is a vertical sectional view on a line corresponding to the line 3—3 of Fig. 1.

Fig. 4 is a vertical section on the line 4—4 of Fig. 5.

Fig. 5 is a section on the broken line 5—5 of Fig. 4, the view being predominantly a horizontal section.

Fig. 6 is a diagram of an illustrative control system in which the invention is embodied.

Referring to the drawings, and particularly to Fig. 6, the dotted line rectangle 10 represents a mining machine of the coal cutter type. The dotted rectangle 11 represents a control mechanism which is, when the mechanism to be controlled is a mining machine, preferably arranged in a control box or the like at a point remote from the point of operation of the machine. The three conductors indicated at 12 are two power conductors and a pilot wire arranged in a cable extending between the box 11 and the mining machine 10.

The mining machine comprises a motor 13 having a series field 14 and a shunt field 15. The direction of rotation of the motor is controlled by a reverse switch mechanism generally designated 16. A pilot switch is illustrated at 17 and a locking mechanism is generally designated 18 and serves, as is later explained, to prevent movement of the reverse switch out of its circuit establishing positions and to hold it sta-

tionary while the motor is revolving at a material speed.

Within the control casing 11, which is shown in a very simple form in the present embodiment, there are arranged a resistor 20, a main contactor 21, a resistance cut-out contactor 22, overload control mechanism generally designated 23, a series relay device generally designated 24, and suitable controlling devices to effect automatic connection of the motor 13 to the line through the resistance 20 and subsequent cutting out of the resistance. The contactor 21 is provided with an operating solenoid 25 of the "half-voltage" type and carries with it an interlock 26. The overload protective device comprises an overload coil 27, a holding coil 28 and a switch element 29. A time delay relay mechanism 30, which may advantageously be of the copper-jacketed coil type, controls a switch 31 which is normally open and delays opening of the latter suitably after the current supply to the coil is interrupted. The resistance cut-out contactor 22 is controlled by a solenoid 33; and the series relay 24 controls a pair of switches 34 and 35, the latter being adapted to introduce a resistance 36 in series with the half-voltage coil 25 previously mentioned. A main line switch is shown at 37 and serves to connect a trolley T and rail R with the conductors in the box 11.

The mining machine 10 has a frame, a portion of which is shown at 40, this frame having a cover plate 41 enclosing a chamber 42 within which the pilot switch 17, the reverse switch 16, and operating means for these switches are housed. The reverse switch comprises a series, herein four, of stationary contacts 44 and a pair of arcuate moving contacts 45. The movable contacts 45 are carried upon a generally circular block 46 of insulating material which forms, with a bottom member 47 and a side wall forming member 48, an enclosure for the contact members 44 and 45. A flange 49 maintains the block 46 in position.

The rotatable block 46 is provided upon its periphery with a series of teeth 51 with which engages a pinion 52 carried upon a longitudinally extending and slidable shaft 53. It will be observed that the shaft 53 is supported near one end, at 55, in the wall of the chamber 42, and that it is provided near its other end with a grooved enlargement 56 adjacent the pinion 52. This grooved enlargement is slidable in a hole 57 formed in a support member 58 and a spring pressed pin 59 is adapted to cooperate with the groove in the portion 56 to maintain the shaft 53 normally in a position in which the pinion 52 and the teeth 51 lie in common planes at right angles to the axis of the shaft 53. In the position of the parts shown in Fig. 5, the pin serves to hold the shaft 53 in the po-

120

sition which it then occupies through engagement with a shoulder 60 at the extremity of the portion 56 remote from the pinion 52.

From Figs. 4 and 5 it will be noted that the member 48 is cut away at its periphery in alignment with the shaft 53 and that the contact carrying block 46 is cut away arcuately adjacent its periphery at two points spaced approximately 90° from each other in such a way that when these are opposite the pinion 52 the latter may be moved into a position materially nearer the plate 47 than is possible in any other positions of the reverse switch mechanism. It will be observed that the block 46 is provided with a shoulder 62 which prevents movement of the pinion 52 into the position shown in Fig. 5 except when one or the other of the recesses 61 is opposite the end of the shaft 53.

The contact carrying member 46 is journaled upon a boss 64 and is resiliently pressed toward the bottom member 47 of the contact enclosing chamber by a spring 65. Mounted for sliding movement upon the frame 58, but insulated therefrom, is a pilot switch member 67 adapted to establish a circuit between stationary contacts 68 and 69. The rod 53 carries a collar 70 which is adapted to engage a plunger 71 and move it against the force of a spring 72 to move the pilot switch member 67 to closed position.

To lock the reverse switch in its different positions a solenoid 75 is arranged to move a locking pin 76 into one or the other of a pair of recesses 77 (of which but one is shown) in the outer face of the contact block 46. The shaft 53 is provided with a hand wheel 78 which is provided with a shoulder 79 arranged to co-operate with a stationary projection 80 to prevent the moving of the handle 78 and the shaft 53 inwardly except in appropriate positions. These positions are determined by a flange 81 and by a recess 82 adapted to receive the stop member 80 on longitudinal movement of the shaft 53. A similar shoulder and recess is provided at the other end of the surface 79 but is invisible in the drawings.

With the foregoing explanation of the construction and arrangement of the parts, the mode of operation of the improved controlling apparatus will be readily understood. The pilot switch 67 is open except when running of the motor is desired, and the reverse switch, in its neutral position, is so disposed that the recesses 61 are equi-distant from the pinion 52. Upon closure of the main line switch 37 a circuit will be established from the trolley line T, through the main line switch, through a conductor 83, a second conductor 84, the normally closed switch 26 and the time delay relay coil 30 to a conductor 85, the other pole of the main line switch 37 and the rail R. Accordingly, the switch 31 will be closed, the coil 33 energized, contactor 22 moved to open position, and flow of current to the motor upon closure of contactor 21 made impossible save through the resistor 20. No further operations in the box 11 will take place until closure of the pilot switch 67.

The machine runner having elected to start the motor will turn the reverse switch to one of its appropriate running positions by rotating the handle 78 until one end of the flange 81 comes up against the stop 80. Rotation of this handle from its "off" position rotates the shaft 53 and pinion 52 which, through engagement with the teeth 51, rotate the contact carrying block 46

to one of the running positions. When a running position is reached, one or the other of the recesses 61 will be opposite the pinion 52 and longitudinal movement of the handle 78 inwardly, which will be permitted by the fact that a recess 82 is opposite the stop member 80 and that a recess 61 is in position to receive the pinion 52, will result in the collar 70 moving the plunger 71 in such manner as to close the resiliently mounted pilot switch 67. When this occurs, a circuit will be established through the holding coil 28 immediately, but no movement of the switch member 29 will be occasioned as the coil 28 has strength only to serve as a holding and not as a moving coil. A circuit will also be established from the trolley T through conductor 83, conductor 84, normally closed overload switch 29, solenoid 25, wire 87, switch 34, pilot wire 88, pilot switch 67, and conductor 85 back to the track R, and the main line contactor 21 will therefore close, putting the motor on the line through the conductor 83, coil 27 of the overload protective device, contactor 21, resistor 20, series relay coil 24, conductor 89 in the cable 12 and back through the conductor 85 to the rail.

The interlock 26 is opened when the contactor 21 closes, and this results in deenergization of the time delay relay coil 30, and as soon as the current has died out in this coil, which requires a little time in view of its arrangement, the switch 31 will drop open, thereby deenergizing solenoid 33 and permitting the contactor 22 to move to closed position, shunting the resistor 20. The motor will then be directly on the line. Energization of the series relay coil 24 moves switch 34 to open position and closes switch 35, which places the resistance 36 in series with the coil 25 thereby cutting down the current consumed in maintaining the contactor 21 closed. It will be evident, since the coil 75 is connected across the motor armature, that immediately upon the supply of current to the motor the locking pin 76 was moved into one of the recesses 77 and the reverse switch is held positively against movement out of the position to which it was brought prior to the closure of the pilot switch.

The stopping of the motor is effected by opening the pilot switch 67 which breaks the circuit through the solenoid 25 allowing the contactor 21 to open; and the parts in the box 11 then return to the position which they occupied prior to the closure of the pilot switch. However, the shaft 53 cannot be rotated until the motor has slowed down to a small fraction of its normal running speed, as the coil 75 connected across the armature is energized by the armature current until the motor speed is largely lost.

From the foregoing description it will be evident that I have provided herein an improved electric controlling system and an improved electric controlling mechanism in which a single handle or other manually operated element may be used both to position a reverse switch and to effect the closure of a pilot switch, that these operations are effected by generically different movements of the operating elements, that the pilot switch can only be closed in one of the "on" positions of the reverse switch and that the reverse switch cannot be moved from one of its "on" positions while the pilot switch is closed or, even after the pilot switch has been opened, while the motor is running at substantial speed. It will further be evident that the parts are not complicated, that the reverse switch is wholly prevented from injury due to the burning of its

contacts, or the like, since it is maintained immovable throughout the period when substantial currents are flowing in the motor, and that all the parts are of substantial and durable construction.

5 While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

15 1. In combination, a motor, a controlling device therefor, reversing mechanism for controlling direction of rotation of said motor, a single operating element for directly actuating the controlling device and the reversing mechanism and having connections with said controlling device and reversing mechanism whereby either may be moved while the other remains stationary, and means for preventing movement of the reversing mechanism until the motor has come substantially to a standstill.

20 2. In a motor controlling apparatus of the type in which means for predetermining the direction of motor rotation and means for establishing and interrupting current supply to a motor are both provided, a motor reversing mechanism movable to predetermine the direction of motor rotation, a motor controlling device whose position determines whether or not current supply to the motor occurs, and controlling means for said reversing mechanism and controlling device including a single initial operating member mounted for two generically different types of operating movements, and means for operatively connecting said member with said reversing mechanism and said motor controlling device operative on but one of said generically different movements of said member to move the reversing mechanism to a running position, and operative on movement of said member directly from its position at the end of said first mentioned movement and solely by the other generically different movement of said member to effect control of said controlling device to start the motor.

25 3. In a motor controlling apparatus of the type in which means for predetermining the direction of motor rotation and means for establishing and interrupting current supply to a motor are both provided, a motor reversing mechanism movable to determine the direction of motor rotation, a motor controlling device whose position determines whether or not current supply to the motor occurs, controlling means for said reversing mechanism and controlling device including a single operating member mounted for a plurality of generically different movements and means for operatively connecting the same with said reversing mechanism and said motor controlling device operative upon one of said generically different movements to move the reversing mechanism and upon a generically different one of said movements to effect control of the controlling device, and means for preventing the second predetermined movement except when said reversing mechanism is in a circuit establishing position.

4. In a motor controlling apparatus of the type in which means for predetermining the direction of motor rotation and means under pilot control for supplying current to the motor initially through a resistance and subsequently with the

resistance cut out are both provided, a reverse switch, means including a pilot switch and controlled by said switch for supplying current to a motor initially through a resistance and subsequently without the resistance, and means operative on rotation thereof to move the reverse switch and on longitudinal movement thereof substantially in the direction in which the axis of its rotation extends to move the pilot switch.

5. In combination, an electric motor, a reversing switch therefor, controlling mechanism for the motor for supplying current thereto initially through a resistance and subsequently with said resistance cut out including a pilot switch, means operative on rotation to move said reversing switch and on longitudinal movement to move said pilot switch, and means for preventing rotative movement after longitudinal movement to effect operation of said pilot switch until the motor is substantially at a standstill.

6. In combination, an electric motor, a reverse switch therefor, controlling mechanism for the motor for supplying current thereto initially through a resistance and subsequently with the resistance cut out, including a pilot switch, a controlling member mounted for rotative movement and for longitudinal movement, operative connections between said member and said reverse and pilot switches whereby on one of said movements movement of one of said switches is effected and on the other of said movements movement of the other of said switches is effected, and means for preventing movement to effect operation of the reverse switch, after movement to effect operation of the pilot switch has been effected, until the motor is substantially at a standstill.

7. In combination, a motor, a controlling device therefor, a reversing mechanism therefor, an operating element operative upon predetermined movement in certain planes to move said reversing mechanism and upon different predetermined movement in other planes angularly related to the planes of movement during reversing mechanism movement, to effect control of the controlling device, and means for preventing movement of said element to move the reversing switch, subsequent to movement thereof to effect control of the controlling device, if the motor is operating above a predetermined speed.

8. In combination, an electric motor, a source of power, a resistance controlling apparatus for said motor for connecting the same to the source of power and for interrupting power supply including means for connecting the motor to the source of power through the resistance and automatically cutting out such resistance, a reverse switch for controlling direction of rotation of said motor, a control circuit for controlling said controlling apparatus and including a pilot switch, means for operating said pilot and reverse switches operative mechanically to preclude closure of the pilot switch until after predetermined movement of the reverse switch, and means for maintaining said reverse switch in the position to which it is brought by said predetermined movement while the motor is rotating at a predetermined speed but permitting movement of the pilot switch, while said reverse switch remains stationary, to effect control of the controlling apparatus.

9. In an electric motor system, a source of power, a resistance, a motor having an armature, controlling apparatus for connecting the same to the source of power and for interrupting power supply including means for connect-

- ing said motor across the line through the resistance and automatically cutting out the resistance, a pilot circuit for setting the automatic apparatus into operation and provided with a 5 pilot switch, a manually operable reverse switch for controlling the direction of rotation of the motor, common operating means for the pilot and reverse switches, interlocking mechanism allowing movement of the pilot switch in either 10 direction between open and closed positions when said reverse switch is stationary in one of its on positions but not otherwise, and preventing movement of said reverse switch while the motor is rotating at a substantial speed, an electro- 15 magnet for controlling the movements of the reverse switch when energized, and a circuit for energizing said electro-magnet by current flow through the armature.
10. In combination, a motor, a controlling device therefor, reversing mechanism for controlling direction of rotation of said motor, means movable with said reversing mechanism for mechanically governing the operation of said controlling device, said means remaining stationary 25 during actual movement of said controlling device, and means for preventing movement of said reversing mechanism until the motor has come substantially to a standstill.
11. In combination, in a motor controlling apparatus, a controlling device for a motor for controlling starting thereof, reversing mechanism for establishing different circuit connections to predetermine the direction of motor rotation, said reversing mechanism having a neutral position, 30 and a single initial operating element for said reversing mechanism and for said controlling device having an "off" position corresponding to the neutral position of the reversing mechanism and to the position of said controlling device when the motor is not running, said operating element being movable selectively in opposite directions from its "off" position to effect motor rotation in opposite directions, each of 35 said opposite motions being of a single generic type, and said operating element being movable directly from its position at the end of either of 40 said direction-predetermining movements by a movement of a single generic type to effect control of the motor controlling device to start the motor, said last mentioned movement of said 45 operating element being the same irrespective of the direction of motor rotation previously predetermined.
12. In combination, in a motor controlling apparatus, a controlling device for a motor for controlling starting thereof, reversing mechanism for establishing different circuit connections to predetermine the direction of motor rotation, said reversing mechanism having a neutral position, 50 and a single initial operating element for said reversing mechanism and for said controlling device having an "off" position corresponding to the neutral position of the reversing mechanism and to the position of said controlling device when the motor is not running, said operating element being movable selectively in opposite directions from its "off" position to effect motor rotation in opposite directions, each of 55 said opposite motions being of a single generic type, and said operating element being movable directly from its position at the end of either of 60 said direction-predetermining movements by a movement of a different single generic type to effect control of the motor controlling

device to start the motor, said last mentioned movement of said operating element being the same irrespective of the direction of motor rotation previously predetermined.

13. In combination, a motor, a controlling device therefor controlling starting thereof, reversing mechanism for controlling direction of rotation of the motor, a single operating element movable in opposite directions from a neutral position to effect rotation of the motor in opposite directions and, irrespective of the direction of motor rotation, having the same motion to effect control of the motor controlling device to start the motor, and means for preventing such last mentioned motion except when said element 80 has been moved from its neutral position to one of its positions for determining the direction of motor rotation.

14. In combination, a motor, a controlling device therefor, a reversing mechanism therefor, an operating element operative upon predetermined movement to move said reversing mechanism and upon a different predetermined movement to effect control of such controlling device, and means for mechanically obstructing the second predetermined movement except when said reversing mechanism is in its circuit establishing position.

15. In a motor controlling apparatus of the type in which means for predetermining the direction of motor rotation and means for establishing and interrupting current supply to a motor are both provided, a motor reversing mechanism movable to determine the direction of motor rotation, a motor controlling device whose position determines whether or not current supply to the motor occurs, and controlling means for said reversing mechanism and controlling device including a single operating member mounted for a plurality of generically different movements, 105 means for operatively connecting the same with said reversing mechanism and said motor controlling device operative upon one of said generically different movements to move the reversing mechanism and upon a generically different 110 one of said movements to effect control of the controlling device, and means for locking said reverse switch in either operative position to which it is moved, brought into locking relation with respect thereto only when said last mentioned movement has occurred.

16. In a motor controlling apparatus of the type in which means for predetermining the direction of motor rotation and means for establishing and interrupting current supply to a motor are both provided, a motor reversing mechanism movable to determine the direction of motor rotation, a motor controlling device whose position determines whether or not current supply to the motor occurs, and controlling means for said 130 reversing mechanism and controlling device including a single operating member mounted for a plurality of generically different movements, and means for operatively connecting the same with said reversing mechanism and said motor controlling device operative upon one of said generically different movements to move the reversing mechanism and upon a generically different 135 one of said movements to effect control of the controlling device, said last mentioned movement 140 being an axial movement of said operating member.

CHARLES W. WYMAN.
